HOPPER FOR SELECTIVELY DISPENSING
TUBE BASESWilliam T. Engel, Union, N. J., assignor to Radio
Corporation of America, a corporation of
Delaware

Application September 16, 1948, Serial No. 49,514

6 Claims. (Cl. 198—33)

1

The present invention relates to conveyors and more particularly to a conveyor system for transporting and suitably orienting irregularly shaped objects taken from a random pile and delivered to a point of utilization in a predetermined position.

Some irregularly shaped objects, such as bases for certain types of electron tubes, include a round flat portion from one face of which contact pins and a locating lug extend, the opposite face being substantially free from any protuberance. Some operations to which such bases are subjected include the step of inserting a metallic shielding member of non-symmetrical configuration into a space provided in the locating lug of the base. This shield is provided with an arm which is required to engage the end portion of a particular contact pin communicating with the flat unobstructed face of the base.

Heretofore it has been the practice for an operator to pick up a base and a shield member and manually turn either one or both of them in several planes until they are in appropriate positions for the shield inserting operation. This practice is time consuming and tiresome for the operator and adds to the cost of the finished product. While these disadvantages of a hand operation have long been recognized, the problems associated with the use of an automatic conveyor system for avoiding these disadvantages have been difficult of solution.

For example, where tube bases are concerned, not only is it necessary that the bases present their flat unobstructed faces to the operator but that the contact pins thereof be radially disposed in a predetermined manner so that the contact pin to be connected to the arm of the shield is always in the same direction from a predetermined reference member on the bases and from the operator.

It is accordingly an object of the invention to provide a conveyor system for irregularly shaped objects having one flat face whereby the objects are first automatically oriented with respect to their flat face and subsequently automatically positioned in such a manner that a predetermined radius of said objects extends in the same direction from a reference point on the objects.

A further object is to provide a conveyor system for picking objects from a hopper with one face of the objects lying in a common plane and delivering the objects with a peripheral reference member on said face in always the same position with respect to an operator.

Another object is to provide a conveyor system having a belt for transporting objects picked

2

up at random from a hopper to a track with said objects in a predetermined position with respect to a reference face thereon, and a means on said track for rotating the objects on an axis normal to said face thereof, for further orienting the objects with respect to an operator.

An additional object is to provide a conveyor system having an overflow means between two elements thereof whereby an excessive capacity of one element does not overtax the capacity of the other element or jam the system.

A further object is to provide a conveyor system having a belt of a variable capacity for picking up objects from a hopper, and a track having a constant capacity to which said objects are delivered and an overflow means between said belt and track.

Another object is to provide a conveyor system having an element wherein irregularly shaped objects are picked up and suitably oriented in one plane by a gravitational force thereon.

A further object is to orient irregularly shaped objects in one plane by gravitational forces and in another plane by mechanical means.

An additional object is to provide a conveyor system wherein a portion of the travel of objects conveyed thereby is accomplished by gravity and another portion of the travel results from mechanically applied forces.

Further objects and advantages of the invention will become apparent as the description proceeds.

Referring to the drawing:

Figure 1 shows a perspective view of the conveyor system of the invention;

Figure 2 shows a fragmentary front view of a portion of the conveyor with special attention directed to the conveyor belt, the gravity travel of the bases on the track and the overflow means;

Figure 3 is a cross-section along the line 3—3 of Figure 2 and shows the structure of a portion of the gravity track;

Figure 4 is a cross-section along 4—4 of Figure 2 and shows a portion of the overflow means;

Figure 5 is a section along 5—5 of Figure 2 and depicts another portion of the gravity track adjacent the conveyor belt;

Figure 6 is a section through 6—6 of Figure 1 and is intended to illustrate the angular disposition of the conveyor belt from the vertical and the agitating means thereon;

Figures 7 and 8 illustrate the principle involved in suitably inclining the belt for picking up an object and holding it in a predetermined position,

Figure 7 indicating the position of the object in which it will be held on and carried by the belt,

while Figure 8 shows an improper position of the object on the belt which will result in the object falling therefrom;

Figure 9 shows partly in section the device of the invention for securing a rotational orientation of the objects carried by the conveyor system;

Figure 10 shows a view along the line 10-10 of Figure 9 and depicts the top of the turret forming part of the rotational orienting means;

Figure 11 is a section along 11-11 of Figure 10 and shows the stepped or offset walls of the object receivers of the turret;

Figure 12 is a view from the top of an element of the rotational orienting means that serves to engage a protrusion on the object being oriented such as the locating lug of a tube base having a raised key;

Figure 13 is a view partly in section along the line 13-13 of Figure 12 and shows a feature of the element of Figure 12 for securing a shock-free engagement between said element and the key on the locating lug of the tube stem;

Figure 14 shows a bottom view of the turret along the lines 14-14 of Figure 9 and illustrates the association of a track with the turret for receiving objects from the turret;

Figure 15 is a section along 15-15 of Figure 14 and shows the manner in which the track engages a tube stem;

Figure 16 is a section along 16-16 of Figure 15 and indicates the relation between the track bars and the contact pins of the tube stem;

Figure 17 is a transverse section of a track of the invention showing a modified form of track; and

Figure 18 is a bottom view of Figure 17.

The hopper and conveyor system of the invention may be described broadly as comprising a hopper for random receipt of objects and a conveyor having two object orienting devices for acting on said objects in a manner to orient them in two perpendicular planes.

Although the invention can be adapted for use in connection with many differently shaped objects, for convenience it will be described solely in association with electron tube bases having a disc-shaped form with one face substantially flat and the other face having a plurality of contact prongs extending therefrom.

Referring to Figure 1, objects such as bases 20 are received in a random manner by hopper 21 and are picked up by belt 22 with their flat faces lying against the belt. To facilitate the picking up of the bases the belt is provided with agitators 27a extending from a surface of the belt. The agitators serve to break up any organization of the bases that opposes transfer thereof to the belt. The bases 20 are carried upwardly by the belt 22 to an open track 23 and a partially closed track 24 which delivers them to a further orienting device 25. This further orienting device rotates the bases on an axis normal to their flat faces until a reference means such as a particular contact prong lies in a desired radial direction from the center of the base. After the bases have been oriented in two perpendicular planes they are sent to a further track 26 by which they are carried to an operator for suitable action, such as dropping a metallic shielding member in the space provided in the locating lug.

The work of the operator is considerably facilitated by the double orientation of the bases provided for by the invention. Thus, the bases are presented to the operator with their flat faces,

from which access is secured to the space in the locating lug, extending upwardly and the contact prong to which electrical contact is required by the shielding member, in a predetermined radial direction from the operator. In this situation the operator needs only to suitably orient the shielding member in a predetermined manner during each inserting operation and after such orientation to drop it into the space provided in the locating lug. The operator is relieved of the necessity of also orienting the base.

Referring more in detail to the invention, the means for orienting the objects in a plane normal to their flat faces will now be described. As shown in Figures 6, 7 and 8, belt 22 is disposed at an angle from the vertical. The degree of angular displacement of belt 22 from the vertical is critical according to the invention, and is determined by the shape of the object to be handled. For example, in handling tube bases it has been found that an angle of about 25 degrees from the vertical represents a satisfactory inclination of the belt for the purposes of the invention. As shown in Figure 7, this angular inclination of the belt 22 results in a retention of the base 20 by the belt when the flat unpronged face of the base lies against the belt. In this case the vertical line A, which passes through the center of gravity of base 20, lies inwardly of the vertical line B, passing through the extremity of support provided by transverse support bars or ribs 27 on the belt. As shown in Figures 2 and 7, therefore, the base 20 is completely supported by the belt 22, the transverse rib 27 and stop bar 28 lying adjacent an edge of the belt for restraining movement of the bases. This restraining function is required because of the inclination from the horizontal of the transverse ribs 27 on belt 22, the purpose of which will be described hereinafter.

While the position of the base on the belt shown in Figure 7 results in an appropriate support for the base, the position of the base shown in Figure 8 results in a lack of such support and a consequent falling of the base from the belt. The reason for the lack of support in the position shown in Figure 8 is the fact that the center of gravity of the base 20 represented by line A lies outside the extremity of the support provided by the transverse support bar 27 represented by vertical line B.

The disposition of the belt 22 at a suitable angle from the vertical therefore assures receipt by it of an object in a desired face relationship to the belt.

This desired face relationship is preserved during the subsequent travel of the objects to a point of utilization. Thus, as shown in Figures 2, 3, 4, 5 and 6, the stop bar 28 extends upwardly along a side of the belt 22 to restrain movement of the base 20 in response to the inclination of the support bar 27 disposed transversely of the belt 22. This inclination should be about 25 degrees from the horizontal. However, above the upper extremity of support bar 28, the bases are free to travel in response to this inclination. To permit such travel to take place in this location there is disposed adjacent the belt a track 23 which is also inclined 25 degrees from the horizontal so as to be in line with the support bars 27 as the front face of the belt travels upwardly. Track 23 is also inclined as shown in Figure 5, in line with the inclination of a back wall of the hopper 21 and is provided with an offset supporting edge 29 to accommodate the

peripheral configuration of base 20. As the track 23 extends from belt 22 it becomes relatively thin at 23a, the purpose of which will become evident as the description proceeds.

As shown in Figure 1, the bases 20 fill a substantial space in the hopper 21. At the lower portion of the hopper the belt 22 is exposed so that bases may be picked up by it. Bases picked up at the lower portion of the hopper are isolated from the bases in a higher level in the hopper by a baffle plate 22a. However, it sometimes happens that travel of the belt 22 through the lower portion of the hopper and the supply of bases, disposes the bases in certain organizations or patterns which render it difficult, if not impossible, for the belt to pick them up. To overcome this difficulty there are provided, according to the invention, agitators comprising pins 27a extending from the belt 22, as shown in Figures 1 and 6. These pins extend outwardly from the belt an appreciable distance and when traveling through the supply of bases in the hopper will readily break up any undesirable disposition thereof. To permit clearance between the wall of the hopper 21 and the pins 27a, slots 21a are provided in said wall above and below the belt 22. Although not shown, the slots 21a below the belt are covered by a resilient pad of rubber or like material, which is provided with closed slots, that permit the pins 27a to force their way therethrough while preventing the passage of bases therethrough.

After base 20 completes its travel on track 23 it reaches a gap 30 provided by track 23a and the space between tracks 23a and 24. The purpose of this gap is to serve as an overflow means. Thus, if the feed of bases to track 24 is more rapid than the utilization thereof, the gap 30 which includes the narrowed track 23a permits bases that cannot be received by track 24, due to crowded conditions thereon, to fall back into the hopper. The gap 30 is wider than a diameter of a base to permit the bases to freely fall therethrough. The relatively thin portion 23a affords a relatively insecure support for a base as shown in Figure 4 and in the event the progress of the base on track 23a should be slowed down or stopped in response to any cause such, for example, as a protruding base on the track 24, the base will due to its insecure support, fall back into the hopper.

After traversing the gap 30 the bases are received by track 24. As shown in Figure 3, track 24 includes rails 31 and 32 provided with retaining plates 33 and 34. The lower rail 32 is disposed with its upper edge slightly below a straight-line continuation of the upper edge of track 23a to allow for a slight drop of the bases as they traverse the gap 30. The retaining plates 33 and 34 are provided to hold the bases on the track during their travel thereon.

It will be noted by reference to Figure 1 that track 24 receives the base 20 in an initial position in which the bases are suitably supported without the retaining plates 33 and 34. However, as travel of the bases continues, the track 24 disposes the bases in positions wherein they would fall from the track in the absence of the plates 33 and 34. Furthermore, while the position of track 24 adjacent the gap 30 utilizes the back wall of hopper 21 in confining the movement of the bases, it will be noted that when the travel extends through the back wall of the hopper through an aperture 35 this back-wall support is lost. The bases on the portion of track

24 extending backwardly of the hopper are disposed with their prong faces extending downwardly and are substantially entirely supported by the retaining plates 33 and 34. In this position the bases are transferred to a second orienting device 25.

A rotating brush 36 having relatively rigid bristles impels the bases upon the end of the track 24 to the orienting device or turret 25. 10 This orienting turret is shown in more detail in Figures 9, 10, 11, 12, 13 and 14. Essentially it comprises an intermittently rotating turret having peripheral recess 37, provided with shoulder 38 for receiving and supporting bases 20 with the pronged faces of the bases turned downwardly. The turret 25 is connected to a suitable power source not shown by which it is given intermittent rotary motion whereby a recess 37 remains stationary adjacent the end of track 24 for a sufficient length of time to permit a base to be inserted in the recess. As shown in Figure 14, this intermittent movement of the turret results in a loading of all recesses between the track 24 and a track 26. When the bases reach 15 position 39 on the turret they are fed on to track 26 with the prongs disposed in uniform radially oriented positions.

The means for radially orienting the bases is 20 shown in detail in Figures 9, 12 and 13. This includes a cylindrical member having a longitudinal slot 41 at its upper tubular portion 42. Member 40 is supported for vertical movement and 25 against rotation on base 43. Lever 44 engaging pin 45 at the lower end of the member 40 may be 30 actuated to cause the member 40 to rise and receive the central lug 46 of the tube base 20. However, the lug 46 can only be received by member 40 when the raised key 47 on the lug is in line with the slot 41 on said member. And 35 when so received the base 20 is suitably oriented rotationally.

Ordinarily the base 20 is not transferred to a 40 recess in turret 25 in such a position that the key 47 enters the slot 41. Therefore, in accordance 45 with the invention, means are employed to rotate the base to a rotational position wherein key 47 enters slot 41. This means comprises a 50 friction pad 48 of relatively soft and resilient material held at the end of a rod-like support 49. The support 49 is in turn held by support 50 for 55 rotary movement only. Belt 51 engaging a pulley, not shown, gives rotary movement to support 49.

Normally, the support rod 49 is constantly rotating. As a recess in turret 25 holding a tube base to be oriented is brought under the pad 48, member 40 is raised to raise a base so that said pad engages the relatively flat face of the base 20. Contact between the base and the pad 48 will 60 impart rotary motion to the base. The lever 44 having been actuated to urge the member 40 against the lower portion of the orienting key 47 on the lug 46, the rotation of the base will cause the key 47 to come into registry with the slot 41, and a force exerted on lever 44 will 65 cause the lug 46 to enter the cylindrical space provided in the upper portion of member 40. This will cause the rotation of the base to stop because it has lost engagement with pad 48. As 70 the member 40 is then lowered, the base, now properly rotationally oriented, is transferred to track 26 by which it is delivered to a utilization point, not shown, where an operator can perform any suitable work on the base such as inserting a shield member therein.

A bevel 41a is provided on the slot 41 to relieve the shock of sudden engagement of the lug 46 by the member 40.

As shown in Figures 15 and 16, the track 26 includes 3 rails, 54, 55 and 56. As oriented rotationally by turret 25, the bases are disposed with their prongs in the manner shown in Figure 16. That is to say, when the bases reach the position 39 on the turret 25, their prongs will be so oriented that rail 55 will enter a path provided between prongs 57, 58 and 59, 60. This engagement of the rail by the base will assure a fixed radial disposition of the base on the track. A rotation of the base on the track is prevented in either direction. The track, however, may be modified according to the invention to accommodate bases having any number of contact pins.

In Figures 17 and 18 is shown a modified form of track 26a having only two rails 62 and 63. This track as well as track 26 utilizes a bar 61 against which the upper face of the base bears, for preventing upward displacement of the base from the track. In this modification the rails 62, 63 pass between four pairs of prongs to firmly hold the base 20 against rotation. This modification is preferred for actual prong bases.

Additional modifications may be made in the invention without departing from the spirit and scope of the appended claims.

What is claimed is:

1. A conveyor system comprising means for agitating a random supply of objects, a belt extending into said supply and having transverse ribs for picking up said objects, and a plurality of tracks for conveying and orienting said objects in a predetermined manner, said means comprising pins extending outwardly from a face of said belt a greater distance than said ribs.

2. A conveyor system for transporting objects from a hopper to a receiving station at predetermined rate and in comprising a movable endless belt having transverse ribs and extending into said hopper, said belt being inclined from the vertical by a predetermined angle, whereby said objects are successively picked up by said ribs, and means on said belt for agitating said objects in said hopper for providing an increased supply of said objects to said belt.

3. A conveyor system including a hopper having an inclined side wall, a plurality of longitudinally inclined tracks extending inwardly of said hopper adjacent said side wall, a support for certain of said tracks, said support comprising an endless belt extending to a lower portion of said hopper whereby said certain of said tracks are adapted to pick up objects disposed in said lower portion of the hopper, stop means for preventing fall of objects picked up by said certain of said tracks, said stop means terminating at a location spaced from the top of said belt, another of said tracks disposed at said location, whereby said objects are free to roll from said certain of said tracks to said another of said track to a utilization point.

4. A hopper comprising a receptacle for receiving a plurality of round objects in random disposition, said receptacle having a relatively high wall inclined outwardly, and an elongated track mounted on said wall and parallel therewith, said track being inclined from the horizontal, whereby said objects are caused to roll on said track to a utilization point, a longitudinal portion of said track being rectilinearly transversely movable to a lower portion of said receptacle for picking up said objects therein and

raising them to a position in registry with the remaining portion of said track, stop means adjacent said longitudinal portion for restraining rolling of said objects thereon, said stop means extending to said remaining portion of said track, whereby said objects are free to roll onto the last named portion of the track when raised from said receptacle.

5. A conveyor for round objects comprising an elongated track having an upper surface inclined longitudinally and transversely, for retaining said objects therein and permitting said objects to roll therealong, a longitudinal portion of said track being rectilinearly movable to pick up objects from a random supply of said objects and to a position in registry with the remaining portion of said track, stop means engaging an end of said longitudinal portion for restraining rolling movement of said objects thereon, said stop means terminating at said remaining portion of the track, whereby said objects are free to roll onto said remaining portion, said remaining portion including a narrowed portion for supporting said objects only when travelling thereon above a predetermined velocity, whereby said objects fall from said track when travelling below said predetermined velocity for releasing an over-supply of objects from said track.

6. In a hopper for dispensing round objects and having a lower portion for accommodating a random supply of said objects and an upper portion including receiving means for said objects, the improvement comprising a composite track for picking up objects from said random supply thereof, and delivering them in a predetermined oriented position and in a rolling movement to said receiving means, said composite track including a movable portion and a fixed portion, said movable portion and fixed portion being inclined longitudinally by the same angular magnitude, a support for said movable portion for moving said movable portion in a predetermined plane from the lower portion of said hopper for picking up objects thereon, to the upper portion of the hopper, said fixed portion of said track being disposed in said plane and adjacent to the path of travel of said movable portion and in the upper portion of said hopper, whereby said movable and fixed portions assume registry at said upper portion, said fixed portion communicating with said receiving means, means for retaining a supply of said objects on said movable portion of the track, and means on said fixed portion for releasing an oversupply of objects fed to said fixed portion.
